[57] **CLAIM**

The ornamental design for a table, as shown and described.

DESCRIPTION

FIG. 1 is a perspective view of a table, showing my new design;

FIG. 2 is a top plan view thereof;

FIG. 3 is a front elevational view, the rear being identical thereto;

FIG. 4 is a side elevational view, the opposite side being identical thereto;

FIG. 5 is a bottom plan view thereof;

FIG. 6 is a perspective view of a table, showing a second embodiment of my new design;

FIG. 7 is a top plan view thereof;

FIG. 8 is a front elevational view, the rear being identical thereto;

FIG. 9 is a side elevational view, the opposite side being identical thereto; and,

FIG. 10 is a bottom plan view thereof.

1 Claim, 2 Drawing Sheets

FIG. 1.FIG. 2.FIG. 3.FIG. 4.FIG. 5.

FIG. 6.FIG. 7.FIG. 8.FIG. 9.FIG. 10.
